UNITED STATES PATENT OFFICE.

MAXIMILIAN CHARLES SCHWEINERT, OF NEW YORK, N. Y.; CARL E. WHITNEY, MAY SCHWEINERT, AND THE FARMERS LOAN AND TRUST COMPANY, EXECUTORS OF M. CHARLES SCHWEINERT, DECEASED.

WALL-BUILDING APPARATUS.

Application filed December 18, 1926. Serial No. 154,387.

My invention relates to means for molding or forming walls or similar structures, employing concrete or the like; and the same has for its object more particularly to provide a simple, reliable and efficient apparatus which is adapted to form the corner portions of the wall intermediate the angularly arranged portions thereof.

Further, said invention has for its object to provide an apparatus of the character specified which is adapted to form a wall having rounded or curved corner portions.

Further, said invention has for its object to provide an apparatus of the character specified in which means is associated with the molding machines employed for forming the straight or angularly arranged portions of the wall to readily and economically provide an intermediate mold chamber adapted to form a corner or intermediate wall portion having certain of the surfaces thereof rounded or curved.

Further, said invention has for its object to provide an apparatus of the character specified in which said molding machines are arranged angularly relative to each other in position to form the angularly disposed portions of the wall, and in which one or more curved plates are interposed between said machines to provide an intermediate mold chamber for forming the intermediate or corner portion of the wall and for imparting to certain of the surfaces of said corner portion a curvature corresponding to the curvature of said plate or plates.

Further said invention has for its object to provide an apparatus of the character specified in which molding machines having slideable extensions thereon are arranged angularly relative to each and are adapted to form the outer or angularly disposed portions of the wall, and in which a curved plate, or plates, is interposed between said extensions and detachably connected thereto to provide an intermediate mold chamber adapted to form the corner portion of the wall and to impart a curvature to certain of the surfaces of said corner portion corresponding to the curvature of said plate or plates.

Other objects will in part be obvious and in part be pointed out hereinafter.

To the attainment of the aforesaid objects and ends my invention consists in the novel details of construction, and in the combination, connection and arrangement of parts hereinafter more fully described and then pointed out in the claims.

In the accompanying drawings showing an illustrative embodiment of the invention,

Fig. 1 is a plan, with parts broken away, of one form of apparatus constructed according to and embodying my said invention;

Fig. 2 is a similar perspective with parts broken away;

Fig. 3 is a similar perspective illustrating an arrangement in which one curved plate is employed;

Fig. 4 is a similar perspective illustrating an arrangement in which sliding plates having curved end portions are employed; and

Fig. 5 is a cross section of the structure or wall formed by or resulting from the use of the form of apparatus illustrated at Figs. 1 and 2.

Referring to the drawings, I have illustrated as one example, my invention applied to molding or wall building machines or apparatus of the type shown, described and claimed in the Van Guilder Patent No. 1,250,394, granted December 18, 1917, although other types of wall molding or building machines or the like may be employed.

Each of the wall molding machines 10 and 11 illustrated comprises outer walls 12, 12^a having hopper extensions or portions 13 at the upper edges thereof. The walls 12, 12^a are supported by the uprights or brackets 14, 14^a secured to the outer sides thereof at the ends and extending upwardly through the hopper portions 13.

Relative movement of the outer walls or members 12, 12^a away from and towards each other, is effected by means of the angle irons or members 15 and 16 disposed one upon the other and arranged in pairs at the opposite ends of each machine. The members 15 and 16 are maintained in sliding relation by means of the bolts 17 carried by the lower members 16 and operating in the slots 18 of the upper members 15.

The brackets or members 14 and 14^a are secured at their upper ends to the outer faces

of the sliding members 16 and 15 by means of bolts or other suitable securing means 19.

Intermediate the outer walls 12, 12^a of each machine 10 and 11 is disposed a collapsible core 20 consisting of the walls 21, 21^a having inwardly directed overlapping flange portions 22 which substantially close the core to prevent access of the plastic material to the interior thereof, the overlapping portions 22 being in slidable engagement to permit of the relative movement of the walls 21, 21^a towards and away from each other.

The walls 21, 21^a are supported by means of the uprights or brackets 23, 24 secured to the inner faces of said walls 21, 21^a at the ends thereof and carried by and secured to the slide bars 16 and 15 like the brackets 14, 14^a are.

Relative movement between the walls of each machine is effected by means of an actuating member 25 having arms 26 pivoted at their ends 27 to the lower slide bars 16 at corresponding ends thereof. Links 28 are pivoted at corresponding ends 29 to the opposite ends of the upper slide bars 15, and at their opposite ends 30 said links are pivotally connected to intermediate portions of said arms 26.

The swinging of the actuating member 25 moves the walls 12 and 21 and the walls 12^a and 21^a in opposite directions, the actuation of said member 25 in one direction moving the walls 12, 12^a inwardly and the walls 21, 21^a outwardly, and the actuation of said member 25 in the opposite direction causing the reverse movement of said walls.

Each core 20 is maintained in operative position against inward movement of the walls 21, 21^a thereof by suitable bracing means, such as that illustrated in said Patent No. 1,250,394, which is controlled by the members 31 pivotally connected at 32 to the links 28.

When the member 25 is actuated to release the machine, the members 31 are raised to release the bracing means to permit of the movement of the walls 21, 21^a towards each other. When the member 25 is actuated in the opposite direction, the bracing means serves to prevent inward movement of said walls 21, 21^a during the tamping of the plastic material in the spaces or molding chambers intermediate the inner and outer walls of said machines.

Each machine 10 and 11 is provided with auxiliary wall portions or slide plates 33 and 34 guided between the uprights 14, and 14^a and walls 12 and 12^a, and serving as extensions for said walls to provide a mold chamber beyond the ends of the machine.

The slides 33 and 34 are preferably removable from the machine so that extensions or slides of other lengths or types may be substituted therefor. Each slide 33 and 34

is secured in adjusted position on the machine by suitable means such as the hand nut 35 operating on a bolt 36 secured to the contiguous wall of the machine and projecting through a slot 37 disposed in one end of the slide plate and arranged to permit of the disengagement of the slide plate from the machine.

The outer end of each slide plate 33, 34 is reinforced by a vertical strip 38 having lateral eyes 39 thereon arranged in vertical alignment so that the slides on two machines may be suitably connected to form a corner portion of the wall to be constructed as hereinafter described.

As shown at Figs. 1 to 4 a pair of machines may be employed to form corners, pilasters, chimneys, flues or other portions, the machines being arranged at various angles according to the angularity of the wall portion to be formed, or according to the character of the portion to be constructed.

My invention permits of the use of the ordinary machines, such as employed to form the straight portions of the wall, in the construction of silos and the like. Heretofore in practice a special type of machine having semi-circular walls has been employed in the construction of silos or other cylindrical buildings. The cost of a complete equipment for building all types of buildings or walls including silos was therefore relatively large. My invention reduces the number of machines necessary to form a complete equipment, and hence, reduces the cost of such equipment.

To effect the economy above mentioned, I construct the silo or other building as illustrated at Fig. 5 with corner portions having rounded or curved inner and outer surfaces 40, 40^a and straight intermediate portions 41, it being essential that at least the inner surfaces 40^a of the corner portions of the building be curved or rounded so that the ensilage, fodder, or other material stored within the building will not be caught or otherwise retained in any angular portions or sharp corners thereof. The structure illustrated at Fig. 5 is of concrete or the like and is provided with a continuous air space 42 intermediate the wall portions thereof.

In order to form the rounded or curved corner portions of the wall to be constructed employing machines such as herein illustrated, the latter are arranged at right angles to each other with the corresponding slide plates 33 and 34 extended as required. Curved plates or members 43 and 44 are interposed between the ends of the corresponding plates 33 and 34 to provide therewith an intermediate mold chamber adapted to form the corner portion of the wall and to impart to the inner and outer surfaces of said corner portion curvatures corresponding to the curvatures of the plates 43 and 44. Each

plate 43, 44 is provided at the ends thereof with latches or locking devices 45 slidably retained thereon and provided with projections 46 adapted to be received within the eyes 39 arranged on the sliding plates 33 and 34. The members 43, 44 are readily placed in position and the latches 45 readily manipulated to engage the plates 33 and 34 whereby the parts are firmly retained in assembled relation. If desired, an angle iron 47 may be disposed vertically at the corner of the wall to be formed in contact with the outer surface of the curved plate 43 whereby to brace the same against outward movement during the tamping operation. The inner plate or member 44 receives the stresses applied thereon during the tamping operation on its convex surface or side and effectively sustains said stresses like an arch. In order to form an air space within the corner portion of the wall to be constructed a suitable angular core 48 is disposed between the walls of the corner forming mold chamber in alignment with the cores 20 of the machines 10 and 11, the core 48 cooperating with the cores 20 to form a continuous air space around the structure formed or constructed.

As illustrated at Fig. 3, if desired, the outer curved plate 43 may be omitted and the outer sliding members or plates 33 of the machines 10 and 11 directly connected by the connecting member 49 provided with projections 50 adapted to engage in the eyes 39. The angle iron 47 is disposed vertically within the angle formed by the connected plates 33. The inner curved plate 44 is disposed in position in the manner described in connection with Figs. 1 and 2. The arrangement illustrated at Fig. 3 permits of the production of a corner wall portion having an angular outer surface and a curved inner surface.

At Fig. 4 is illustrated another form of my invention in which either the inner pair or both pairs of sliding plates or extensions 33 and 34 illustrated at Figs. 1 to 3 are replaced by sliding plates or extensions 33^a and 34^a having curved outer end portions 51. To provide the intermediate mold chamber for forming the rounded corner wall portion, the plates 33^a and 34^a are extended until the ends thereof engage, and the same are then locked or secured together by the cooperating locking devices 51^a illustrated, or by other suitable means.

In operation, either machine 10 or 11 or both may be employed in constructing the straight portions of the wall to be formed. When the corner portion is to be formed, the machines are disposed at an angle relative to each other, and actuated to place the same in operative position. The curved plate or plates 43 and 44 are then disposed in position between the slides 33 and 34 to pro-

vide the intermediate mold chamber. After the machines have been actuated to place the walls thereof in operative position, the core 48 is placed in position.

The plastic material or concrete is now introduced into the mold and suitably tamped. After the corner portion of the wall has been formed, the core 48 and plates 43 and 44 are removed and the machines actuated to disengage the same from the newly formed portion of the wall to permit of the removal or movement of said machines without damaging the surfaces of the wall.

It is to be noted that in my said invention the machines employed to form the straight portion of the wall may also be employed to form either rounded or angular corner portions of the wall. These machines are readily adapted to form rounded or curved corner wall portion by inserting between the extensions or slides thereof the curved plates above described, or by replacing the ordinary slides thereof by the slides having outer curved portions, the former arrangement, that illustrated at Figs. 1 to 3, being the preferred form as the plates 43 and 44 may be more readily placed in position and removed without disturbing the position of the machines.

My invention permits of the construction of silos or the like having rounded corner portions, and possessing all of the advantages of the ordinary cylindrical silo, with the ordinary apparatus employed for forming straight wall portions. The inclusion of special and expensive apparatus for forming silos or cylindrical buildings as a part of the complete equipment for constructing hollow walls is therefore made unnecessary.

Having thus described my said invention, what I claim and desire to secure by Letters Patent is:

1. The combination of a pair of molding machines arranged angularly relative to each other, and each including parallel members providing a wall molding chamber therebetween, and means for actuating the wall molding members of each machine to move the same to and from operative position, with members slidable on and connecting said machines and providing an intermediate molding chamber for forming the corner portion of the wall; certain of said last named members including a portion having a curved inner surface, whereby to impart a corresponding curvature to the contiguous surface of the corner portion of the wall to be formed in said intermediate mold chamber.

2. The combination of a pair of molding machines arranged angularly relative to each other, and each including wall forming members and members slidable thereon adapted to form extended wall molding chambers therewith, and means for actuating the wall

forming members of each machine to move the same to and from operative position, with a plate disposed between and connected to the ends of certain of the corresponding slide-
5 able members of said machines to form an intermediate corner molding chamber; said plate having a curved inner surface for imparting a corresponding curvature to the contiguous surface of the corner portion of
10 the wall to be formed in said intermediate molding chamber.

3. The combination of a pair of molding machines arranged angularly relative to each other, and each including wall forming members and members slideable thereon adapted to form extended wall molding chambers therewith, with a curved plate disposed intermediate the ends of certain of said slide-
15 able members, and means for detachably se-
20 curing said plate thereto.

4. The combination of a pair of molding machines arranged angularly relative to each

other, and each including parallel members providing a wall forming chamber therebetween, and members slideable on said first-
25 named member to form extensions thereof, and means for actuating the wall forming members of each machine to move the same to and from operative position, with a se-
parate plate disposed between the ends of the inner slideable members of said machines, means for detachably securing said plate thereto; said plate having a convex inner surface for imparting a corresponding curvature to the inner surface of the corner of
30 the wall to be formed, and means for detachably securing the outer of said slideable mem-
bers together.

Signed at the city of New York, in the county and State of New York, this 12th ⁴⁰ day of November, one thousand nine hundred and twenty-six.

M. CHARLES SCHWEINERT.
